UNITED STATES PATENT OFFICE.

MELCHESEDECK Y. THOMPSON, OF ARKADELPHIA, ARKANSAS, ASSIGNOR
OF ONE-HALF TO AUSTIN M. CROW, OF SAME PLACE.

PRESS FOR WHEAT-BRAN, &c.

SPECIFICATION forming part of Letters Patent No. 293,603, dated February 12, 1884.

Application filed November 28, 1883. (No model.)

To all whom it may concern:

Be it known that I, MELCHESEDECK Y. THOMPSON, a citizen of the United States, residing at Arkadelphia, in the county of Clark 5 and State of Arkansas, have invented certain new and useful Improvements in Presses for Wheat-Bran and other Articles; and I do declare the following to be a full, clear, and exact description of the invention, such as 10 will enable others skilled in the art to which it appertains to make and use the same, reference being had to the accompanying drawings, and to letters or figures of reference marked thereon, which form a part of this 15 specification.

Figure 1 of the drawings is a representation of a side view of this invention. Fig. 2 is a vertical longitudinal sectional view. Fig. 3 is an end view. Fig. 4 is a sectional end view. 20 Figs. 5, 6, 7, and 8 are detail views.

This invention has relation to presses for wheat-bran, cotton, or hay; and it consists in the construction and novel arrangement of devices, as hereinafter set forth, and particularly pointed out in the appended claims. 25

The object of this invention is to utilize the effective force of two screws having their threads reversed with respect to each other, so that pressure will be applied to the mass in 30 the baling-box in opposite directions, and to utilize the mass and leverage of the baling-box in working the screws.

In the accompanying drawings, the letter A designates the frame of the press, which should 35 be solidly constructed, having the end uprights or pillars, B, which are bound together by means of longitudinal ties and sills, as at C C, to withstand pressure outward upon the pillars.

The baling-box D is of horizontally-elongated 40 rectangular form, having four substantial horizontal timbers, a a, forming the corners of the framing, and supporting the side boards, b b.

An opening is left at c, in the middle portion of the box, for the escape of the pressed article.

45 At each end of the box three sides, b, are permanently secured to the framing-bars a. The fourth sides, d, are the doors, which are removable, and are provided with rings or handles e, whereby they may be adjusted or taken 50 away from the box. These doors d are se-

cured in place by means of the wedge-blocks i, which are inserted under the iron straps E, which encircle the box and bind the timbers thereof firmly together. The inner ends of the box-boards b b and of the movable doors 55 d d are beveled on their inner sides, as indicated at g, to receive the outer edges, h, of the headless press-box F, which is designed to fit in the middle portion of the baling-box, between the end portions G G, which are provided with permanent side boards, as hereinbefore described. When the middle headless box or rectangular tubular section, F, is put in position between the end portions G G of the baling-box, a continuous baling-chamber is 60 formed between the ends or heads H H of the baling-box. Within this chamber, on each side, are the followers K K, which move in opposite directions toward the middle portion of the box, and are provided with the screw-stems 70 L L, which have their threads reversed with reference to each other, said screw-stems passing through central openings, h, in the ends or heads H of the baling-box, and through fixed nuts l in the pillars B of the frame. 75

In the chamber of the baling-box, between the followers and the headless box or packing-box F, are placed the loose heads m, adapted, when the followers move toward the box F, to be carried thereto, as the material in the baling-box is compressed, until, the pressure being complete, the heads m enter the ends of the baling-box. These heads are then to be nailed in position to the box F, and then, the movement of the screws being reversed, the 80 wedges and doors are removed, and the packing-box, with its contents, is allowed to drop out of the baling-box. Another headless box can then be introduced into position for a fresh charge. The screws are reversed by the 85 rotation of the baling-box, which turns the followers to which they are secured.

M M indicate the circular cast ends of the baling-box, one or both of which may be provided with peripheral teeth to engage a drive-wheel, N, having a shaft, n, extending through a bearing in the upright, and serving to receive a pulley, p, which may be turned by power. The ends M and their wooden inner sections, P, are firmly bolted to the ends of the hori- 95 100

zontal timbers of the baling-box, the bolts being secured by countersunk nuts near the ends of said timbers. The bands or straps which encircle the baling-box are made with re- 5 versely-threaded ends *q*, said ends being connected by a rotary coupling or double nut, which can be turned to tighten the bands when necessary. The screw-stems *L* of the followers extend through the openings *k* of the ends 10 of the baling-box, and form journals on which the box turns. The end castings, *M*, of the box are formed with collar projections *r* around the openings *k*, which serve to bear against the inner walls of the large nuts, while the journal 15 portions *t* of said nuts pass through said openings in the cast ends. In the rims of the wooden circles *P* are secured radially-projecting han- 20 dles *s*, whereby the box can be turned manually when power is not used. The follow- 25 blocks are of ordinary construction, each hav- ing a collar-plate, *n'*, bolted to its back, and formed with a central bearing for the end of the screw-stem, which is designed to be re- ceived into the follow-block, and to be secured thereto by means of a transverse pin, *v*, pass- 30 ing through a slot, *x*, in the follower and a slot in the end of the screw-stem.

R indicates a locking-pin or movable stop having a bearing in the frame, and adapted to 35 be placed in position to engage a portion of the baling-box, to hold it steady and keep it from turning when it is being filled. The large bearing-nuts *l* are set into the pillars of the frame, and are secured thereto by means of 40 transverse bolts *z*, which engage transverse bearings *w*, made in the upper and lower portions of said nuts.

While this press may be used for any sub- 45 stance, it is especially adapted to compress wheat-bran into small compass for shipment. The force required is not great, and the bran is packed with remarkable density.

The side boards of the press are usually per- 45 pass outward, as well as to afford conductive

means to the electricity developed as the bran or other substance is being compressed by the movement of the followers toward each other.

Having described this invention, what I claim, and desire to secure by Letters Patent, 50 is—

1. The rotary baling-box consisting of the cast ends and their center bearings, the horizontal corner timbers and their side boards and doors at each end, and the middle opening for the 55 packing-box, substantially as specified.

2. The combination, with a rotary baling- 60 box having chambers at opposite ends, formed by beveled-edged boards and doors, of the headless packing-box having bevel-edges, and the straps and fastening-wedges of the baling- box, substantially as specified.

3. The combination, with a rotary baling- 65 box having cast and peripherally-toothed cir- cular ends, of the large fixed bearing-nuts, the followers having reversely-threaded screw- stems, and the driving cog-wheels engaging the teeth of the cast ends, substantially as specified.

4. The rotary press-box having the followers 70 in opposite ends and their reversely-threaded screw-stems, the end castings and the wooden circles having radial handles, and the binding-straps encircling the timbers of said press- box, substantially as specified.

5. The combination, with a rotary press- 75 box having end chambers and a middle opening, of a headless packing-box in the middle opening, oppositely-moving followers in the end chambers having reversely-threaded screw-stems, and loose heads of the packing- box moving in the end chambers with the fol- lowers to the packing-box, substantially as specified.

* In testimony whereof I affix my signature in 85 presence of two witnesses.

M. Y. THOMPSON.
